MOP CONE WRINGER

Frank J. Pudelko and Virginia M. Pudelko, Gordon, and
Lloyd T. Hinn and Leslie L. Hinn, Rushville, Nebr., as
signors to H & P Manufacturing Corp., Rushville, Nebr.,
a corporation of Nebraska

Filed Oct. 10, 1968, Ser. No. 13,925

Term of patent 14 years

Int. Cl. D7—06

U.S. Cl. D49—29

FIGURE 1 is a perspective view of a mop cone wringer showing our new design;

FIGURE 2 is a top plan view of the mop cone wringer of FIGURE 1;

FIGURE 3 is a side elevational view thereof;

FIGURE 4 is another side elevational view of our mop cone wringer;

FIGURE 5 is a bottom view thereof, and

FIGURE 6 is another side elevational view thereof.

We claim:

The ornamental design for the mop cone wringer, as shown.
